UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed February 26, 1921. Serial No. 448,047.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

The present invention relates to typewriting machines of the continuous billing variety, one form of which is set forth in the patent to Wernery & Smith, No. 1,132,055, granted March 16, 1915, and provides a means for trimming the side edges of a 10 fan-fold web used in such machines, thus remedying such objections which have arisen in connection with the use of such webs in machines of this type.

The fan-fold webs used in continuous 15 billing machines are perforated at their edges to facilitate the folding and the accurate superposing of the printed forms. When the sheets of the web are separated after typing, the perforations leave a ragged edge which detracts from the general 20 appearance of the bill. Users of fan-fold webs sometimes trim the side edges of the webs before introducing them into the machine. This is objectionable, however, 25 since the separate sheets tend to creep relatively to each other in the operation of feeding them around the platen while typing the forms. It is therefore desirable to 30 trim the side edges of the web in such manner as to provide smooth edges on the separate sheets without permitting creeping of the sheets. For this purpose there is 35 mounted at the rear of the carbon-paper carriage, at each side thereof, a cutting 40 blade exterior to the web and disposed in a plane at right angles to that of the web and inclined to the side edge thereof so as 45 to project into said web, and a guide co-operating with each cutting blade for guiding the web into the cutting blades, so that, 50 upon retraction of the carbon-carrier, the blades will trim off and throw aside portions of the edges of the web and separate the latter into sheets. This is done at the portion of the web which is not separated

or spread by the carbon-holding blades, between which the web is threaded. Only the portion about to be typed is trimmed, the remainder of the web remaining united at the edges, thus guarding against relative shifting of the sheets. The rapid rearward movement of the sharp blades and co-operating guides will result in a clean cut, leaving the separate sheets of the web with smooth, even edges. Means may be provided for adjusting the height of the cutting blade, and also the distance which the blade projects into the web. 55

To obviate the necessity of frequently changing the blades, they may be circular 60 in form so that progressive sharp portions of the periphery may be utilized in place of the used, dull ones.

Other features and advantages will hereinafter appear. 70

In the accompanying drawings,

Figure 1 is a perspective view of a continuous billing machine with the invention applied thereto, only such parts of the machine being shown as directly co-operate 75 with the invention.

Figure 2 is a longitudinal vertical section of the device shown in Figure 1.

Figure 3 is a plan view of the device shown in Figure 1. 80

Figure 4 is a detail showing a modified form of cutting-blade.

In the drawings, 10 is a platen of the fan-fold machine of the type disclosed in the aforesaid Wernery & Smith patent. 85 The platen forms part of the usual carriage (not shown) which is provided with a rearward extension comprising side rails 11 and 12 which form runways for a carbon-carrier or carriage 13. A web of work-sheets 20 is fed from any suitable source from the rear to and over carbon-carrier 13, over guide-bar 21, and thence under and around the platen to the printing point. 90

The carbon-carrier is provided with the usual stepped side-supporting members 22, having detachably connected therewith the inwardly-extending carbon attaching bars or fingers 23, said fingers being projected alternately from opposite sides at different 95 100

prior to typing on said section, disconnecting the superposed plies of said web to an extent corresponding to the range of movement of said carbon-carrier and forming 5 smooth edges upon the disconnected sections of the plies, and leaving the remainder of the web uncut, preparatory to further typing operations thereon.

2. In a continuous billing typewriting machine comprising a carriage, and a platen journaled in said carriage and around which a fan-folded web of sheets may be fed in combination, a rearward extension of said carriage, a carbon-carrier through which the 15 web is threaded, said carbon-carrier mounted for forward and rearward movement on said extension, and means mounted on said carbon-carrier exterior to the web for trimming off strips at each side edge of said web 20 to disconnect said sheets and to produce smooth side edges therefor, said trimming means being rendered effective by the movement of the carrier relative to said web, said carbon-carrier located between the trimming 25 means and the platen.

3. In a typewriting machine, in combination, a platen over which a fan-fold web may be fed, a reciprocable carbon-carrier for withdrawing carbon-sheets from a used portion 30 of the fan-fold web, the web threading through said carbon-carrier, and smooth-trimming means exterior to the web and connected to said carbon-carrier and rendered effective by a withdrawing movement of 35 said carbon-carrier to trim off a portion of the folded side edges of a section of said fan-fold web, prior to typing on said section, to disconnect the superposed plies of said web for a length corresponding to the 40 range of movement of said carbon-carrier and to leave smooth edges upon the disconnected plies, said trimming means comprising a single trimmer at each side of the fan-fold web and operative upon the web in 45 advance of its passing through the carbon-carrier.

4. In a typewriting machine, in combination, a platen over which a fan-fold web may be fed, a reciprocable carbon-carrier for 50 withdrawing carbon-sheets from a used portion of the fan-fold web, the web threading through said carbon-carrier, and smooth-trimming means exterior to the web and mounted on said carbon-carrier at its rear 55 and effective upon the web before it opens to pass through the carbon-carrier and rendered effective by a withdrawing movement of said carbon-carrier to cut off a portion of the folded side edges of a section of said 60 fan-fold web, prior to typing on said section, to disconnect the superposed plies of said web and to leave smooth edges upon the disconnected plies, while the remainder of the web remains uncut, preparatory to further 65 typing operations thereon, said trimming

means comprising for each side a knife to cut all of the plies, each knife being in a plane perpendicular to said web and having its cutting edge inclined so as to effect a draw-cut on said plies prior to the separation 70 thereof effected by the carbon-carrier.

5. In a typewriting machine, in combination, a platen over which a fan-fold web may be fed, a reciprocable carbon-carrier for withdrawing carbon-sheets from a used portion 75 of the fan-fold web, smooth-trimming means exterior to the web and mounted on said carbon-carrier at its rear and rendered effective by a withdrawing movement of said carbon-carrier to trim off a portion of the folded side edges of a section of said fan-fold web, prior to typing on said section, to disconnect the superposed plies of said web and to leave smooth edges upon the disconnected plies, said trimming 80 means comprising for each side at which trimming is to be effected a knife to cut all of the plies, said knife being in a plane perpendicular to said web and having its cutting edge inclined so as to effect a 85 draw-cut on said plies, and a guide adjacent each knife and holding the plies in compact relation where they are presented to said inclined cutting edge, said guides also co-operating to prevent edgewise displacement 90 of the web.

6. In a typewriting machine, in combination, a platen over which a fan-fold web may be fed, a reciprocable carbon-carrier for withdrawing carbon-sheets from a used portion 100 of the fan-fold web, smooth-trimming means mounted on said carbon-carrier at its rear and rendered effective by a withdrawing movement of said carbon-carrier to cut off a portion of the folded side edges of a section of said fan-fold web, prior to typing on said section, to disconnect the superposed plies of said web and to leave smooth edges upon the disconnected plies, said trimming 105 means comprising for each side at which trimming is to be effected a knife to cut all of the plies, said knife being in a plane perpendicular to said web and having its cutting edge inclined so as to effect a draw-cut on said plies, and a guide comprising portions to engage the web on opposite site faces to present the folded side edges in 110 compact condition to said knife.

7. In a typewriting machine, in combination, a platen over which a fan-fold web 120 may be fed, a reciprocable carbon-carrier for withdrawing carbon-sheets from a used portion of the fan-fold web, smooth-trimming means mounted on said carbon-carrier at its rear and rendered effective by a withdrawing movement of said carbon-carrier to cut off a portion of the folded side edges of a section of said fan-fold web, prior to typing on said section, to disconnect the superposed plies of said web and to leave 125 130

- smooth edges upon the disconnected plies, said trimming means comprising for each side at which trimming is to be effected a knife to cut all of the plies, said knife being 5 in a plane perpendicular to said web and having its cutting edge inclined so as to effect a draw-cut on said plies, and means to permit the width of the cut-off portion to be varied, comprising a mounting for said 10 knife such that the latter may be moved inwardly and outwardly with reference to the adjacent side of the web and may be secured in adjusted position.
8. In a typewriting machine, in combination, a platen over which a fan-fold web may be fed, a reciprocable carbon-carrier for withdrawing carbon-sheets from a used portion of the fan-fold web, smooth-trimming means mounted on said carbon-carrier at its 15 rear and rendered effective by a withdrawing movement of said carbon-carrier to cut off a portion of the folded side edges of a section of said fan-fold web, prior to typing on said section, to disconnect the superposed 20 plies of said web and to leave smooth edges upon the disconnected plies, said trimming means comprising for each side at which trimming is to be effected a knife to cut all of the plies, said knife being in a plane perpendicular to said web and having its cutting edge inclined so as to effect a draw-cut on said plies, and an adjustable mounting for said knife such that the latter may be 25 shifted to change the portion of its edge used for cutting off the folded side edges of said web.
9. In a continuous billing typewriting machine comprising a carriage, and a platen journaled in said carriage and around which 30 a web of sheets is adapted to be fed, in combination, an extension of said carriage, a carbon-carrier mounted for forward and rearward movement on said extension, and means including a knife mounted on the rear of said carbon-carrier for cutting off an edge portion of said web to disconnect sheets at that edge and to provide smooth edges for said sheets where cut, said cutting means being rendered effective by a rearward movement 35 of the carrier relative to said web, said knife being so mounted in a plane perpendicular to the plane of said web that it may be adjusted vertically to bring different portions of the knife into the plane of said web.
- 55 10. In a continuous billing typewriting machine comprising a carriage, and a platen journaled in said carriage and around which a web of sheets is adapted to be fed, in combination, an extension of said carriage, a carbon-carrier mounted for forward and rearward movement on said extension, and means for cutting off a portion of a side edge 60 of said web to disconnect the sheets joined at that edge and to leave the sheets with 65 smooth edges, said cutting means including a knife mounted on the rear of said carbon-carrier adjacent the edge of said web to be cut off, said cutting means being rendered effective by a rearward movement of the carrier relative to said web, said knife being 70 mounted in a plane perpendicular to the plane of said web and inclined with respect to the edge of said web, so that the knife may project inwardly beyond the edge of said web a distance corresponding to the 75 width of the strip which it is desired to cut off from the web.
11. In a continuous billing typewriting machine comprising a carriage, and a platen journaled in said carriage and around which a web of sheets is adapted to be fed, in combination, an extension of said carriage, a carbon-carrier mounted for forward and rearward movement on said extension, a guide mounted on the rear of the carrier and through which the adjacent side edges of the sheets of said web pass as a compact mass, and a knife mounted on said carrier adjacent said guide and rendered effective 80 by a rearward movement of said carrier to cut off portions of the side edges of said sheets as they emerge from the guide to disconnect said sheets and leave them with smooth edges, said guide preventing displacement of the web by the knife during 85 the cutting operation.
12. In a machine of the character described, the combination with a carbon-carrier through which a longitudinally folded work-web is threaded, of means on the rear of said carrier to trim off a folded side edge of the web, before advancing through and being opened up by the carrier, to disconnect the plies of a section of the web and leave the latter with smooth edges, said trimming means comprising at a side edge a knife exterior to the web and cutting through all of said plies, said knife being rendered effective by relative movement of the carrier and the web longitudinally of the latter, to an extent dependent upon such movement, leaving the remainder of the web whole preparatory to further typing operations thereon, and means supporting the web at said knife.
13. In a continuous billing typewriting machine comprising a carriage, and a platen journaled in said carriage and around which a web of sheets may be fed, in combination, an extension of said carriage, a carbon-carrier mounted for forward and rearward movement on said extension, guides mounted on the rear of the carrier, one on each side thereof, each of said guides having a narrow opening through which the sheets of the web pass horizontally in a compact mass, and means rendered effective by a rearward movement of the carbon-carrier for cutting off portions of the side edges of said web to disconnect said sheets and provide smooth

- edges therefor, said cutting means comprising knives mounted on said carrier adjacent said guides and lying in planes perpendicular to the plane of the web, whereby the 5 edges of the compact mass of sheets of said web will be cut off adjacent the guides.
14. In a machine of the character described, the combination with a carbon-carrier, of means at the rear of said carrier to 10 cut off the folded side edges of a web, before advancing through the carrier, to disconnect the plies of the web and leave the latter with smooth edges, said cutting means comprising at one side edge a knife exterior 15 to the web to cut through all of said plies, and means effecting relative movement of the carrier and the web longitudinally of the latter, and concomitantly rendering said knife effective to an extent dependent upon 20 such relative movement, and a guide to hold the web at the side adjacent said knife to prevent displacement of the web during the cutting action of the knife.
15. In a typewriting machine, the combination of a platen over which a web may be 25 fed, a carbon-carrier, the carbon-carrier and the web being relatively movable in a direction lengthwise of the web, said web comprising several layers folded at a side 30 edge of said web, a knife exterior to the web and lying in a plane perpendicular to that of the web, and means rendering said knife effective for trimming off the fold from said web to disconnect said layers and 35 leave the latter with smooth edges, and concomitantly effecting a relative shift between the web and the carbon-carrier.
16. In a typewriting machine, the combination of a platen over which a fan-fold 40 web may be fed with interleaved carbon-sheets, a carbon-carrier from which the carbon-sheets extend and through which the web is threaded, and means for disconnecting the plies of said web and leaving the 45 disconnected plies with opposite smooth edges, said disconnecting means comprising a duplex cutter device exterior to the web and perpendicular to the plane of the web, said cutter device being connected with 50 said carbon-carrier to be operated thereby to trim off a portion of the web at the adjacent side edges thereof in advance of opening up and passing through said carbon-carrier.
55. 17. In a typewriting machine having a platen and means for presenting a side-folded web thereto, and carbon-holding blades introduced between the plies of the web and separating said plies, the combination 60 with means for effecting a relative shift between the carbon-holding blades and the folded web, of means outside the separated area of the plies and exterior to the web for trimming off the side edge of the folded web
- concomitantly with said shifting operation and to an extent corresponding to the extent of shift, said trimming means including a cutter and means at said cutter to support the web.
18. In a typewriting machine having a 70 platen and means for presenting a fan-fold web thereto, and carbon-holding blades introduced between the plies of the web and separating the same, the combination of means outside the separated area of the plies 75 and exterior to the web for trimming off the side edges of the fan-fold web, and means to operate said trimming means.
19. In a typewriting machine having a 80 platen and means for presenting a fan-fold web thereto, and carbon-holding blades introduced between the plies of the web and separating said plies, the combination with means for effecting a relative shift between the carbon-holding blades and the fan-fold 85 web, of means outside the separated area of the plies and exterior to the web for trimming off the side edges of the fan-fold web concomitantly with said shifting operation, and to an extent corresponding to the extent of the shift.
20. In a typewriting machine having a 90 platen and means for presenting a fan-fold web thereto, and carbon-holding blades introduced between the plies of the web and separating said plies, the combination with means for effecting a relative shift between the carbon-holding blades and the fan-fold 95 web, of means outside the separated area of the plies and exterior to the web for trimming off the side edges of the fan-fold web concomitantly with said shifting operation, and to an extent corresponding to the extent of the shift, said trimming means comprising cutters, one for each side of the fan-fold web, and means at said cutters to support the edges of the web at the trimming 100 operation.
21. In a typewriting machine having a 105 platen and means for presenting a fan-fold web thereto, and carbon-holding blades introduced between the plies of the web and separating said plies, the combination with means for effecting a relative shift between the carbon-holding blades and the fan-fold 110 web, of means outside the separated area of the plies and exterior to the web for trimming off the side edges of the fan-fold web concomitantly with said shifting operation, and to an extent corresponding to the extent of the shift, said trimming means comprising cutters, one for each side of the fan-fold 115 web, and means at said cutters to compact the web.
22. In a typewriting machine having a 120 platen and means for presenting a fan-fold web thereto, and carbon-holding blades introduced between the plies of the web and

separating said plies, the combination with means for effecting a relative shift between the carbon-holding blades and the fan-fold web, of means outside the separated area of 5 the plies and exterior to the web for trimming off the side edges of the fan-fold web concomitantly with said shifting operation, and to an extent corresponding to the extent of the shift, said trimming means being in

rear of the carbon-holding blades and trimming off the folded edges in advance of the area of the plies separated by the carbon-holding blades. ¹⁰
